UNITED STATES PATENT OFFICE.

LESLIE MCCHARG, OF FREEPORT, NEW YORK.

PIER-DOOR.

1,369,425.

Specification of Letters Patent. Patented Feb. 22, 1921.

Application filed June 5, 1920. Serial No. 386,673.

To all whom it may concern:

Be it known that I, LESLIE MCCHARG, a citizen of the United States, residing at Freeport, in the county of Nassau, State of New York, have invented certain new and useful Improvements in Pier-Doors, of which the following is a full, clear, and exact description.

The invention forming the subject of this application for Letters Patent is an improvement in doors for pier sheds, freight warehouses and the like, and which are composed of two sections adapted to slide vertically until one overlaps the other and then to move laterally until the two sections lie in a substantially horizontal position.

Doors of this general character are very widely used. The fact that they are necessarily somewhat massive and of considerable weight makes their ready and easy operation difficult and the means for such operation expensive and complicated, which objections I have sought to and have succeeded in overcoming by the construction that characterizes my present improvement.

According to my invention I employ two vertically sliding sections, counterbalanced by a weight equal to both, but arranged to move at one-half of the speed of the rising lower section and at the same speed as the two overlapping sections, so that no greater power is required to lift one section than the two. I also apply the counterbalancing weight in such manner that either or both sections are always perfectly balanced, in whatever position or relation they may be, and to the doors I attach certain accessory means for preserving them at all times in their proper relative positions without regard to ordinary conditions, such as frictional contact or other causes.

My improvements are illustrated in the accompanying drawings, in which:

Figure 1 is a view in side elevation of the door, the framework being indicated by dotted lines.

Fig. 2 is a top plan view of the same, parts of the framework being indicated in dotted lines.

Fig. 3 is a front elevation of a portion of the door; and

Figs. 4, 5, 6 and 7 are details of a latching mechanism attached to the door which is or may be used to prevent their displacement from their normal and proper relative positions.

In its main features of construction and operation the door is similar to many others of its class and comprises an upper section 1 and a lower section 2 adapted to slide vertically, the lower section under guide plates 3 secured to the upper section. A spindle 4 is mounted above the door and provided with a sprocket wheel 5 which is turned by means of an endless belt or chain 6 for opening or closing the door, and the motion of this sprocket is communicated by a chain 7 and sprockets 8 and 8' of proper relative diameters to raise the speed to a shaft 9, mounted above the two door sections. The above devices are common in this class of door.

To the middle points 10 on the side edges of the upper section of the door are connected sprocket chains 11 which run over sheaves 12, loose on shaft 9, then under sheaves 13, carried by counterbalance weights 14, then up over sheaves 15 secured to shaft 9, and thence to the bottom of the lower section 2 where they are connected to arms or brackets 16.

From the construction it follows that if the chain 6 be pulled to rotate the sprocket 5, the shaft 9 is rotated and the chain 11 pulled up raising the lower section of the door. During this operation the upper section is not moved and by reason of the connections shown and described the counterbalance weights move downward but at one-half the speed at which the lower door section moves up. This continues until the lower section fully overlaps the upper.

Secured in any proper manner, as to the roof beams, are two guideways 17 with rounded and downwardly inclined ends, and rollers 18 secured to brackets 19 on the upper part of the upper door section enter these guideways. When, therefore, the lower section fully overlaps the upper, the force applied to the chain 11 moves both upper and lower sections together, and the top of the upper section is carried out laterally and follows the guide way until the two sections lie in a substantially horizontal position, or at right angles to their former position of rest.

During the upward movement of the door sections the counterbalance weights manifestly move at twice their former speed, or at the same speed as the door sections are moving, but the weights are sufficient to counterbalance both sections, so that no

greater power is required to lift the lower section when the weight is moving at half speed than is now required to raise both sections while the weight is moving at its full rate. It also results from the fact that the chain 11 is connected to the middle points of the upper section that the entire door will be exactly counterbalanced in all positions, variable portions of the weight being carried by the horizontal guides and by the chains.

It may happen that frictional contact between the two door sections or other causes will operate to move one section improperly with reference to the other. For example, in opening the door the lifting of the lower section might start the upper section in movement which is not wanted, and to prevent this I secure to the top of the upper section a form of latch which prevents such displacement.

This device is shown in detail in Figs. 4 to 7, and consists of two pivoted latches 20 and 21 on pivots 22 carried on the upper edge of the door section. One of these latches 21 has at the end of one arm a catch 23 which, in the normal position of the upper door section, engages with a fixed stop 24 on the door jamb and prevents the said section from rising. When, however, the lower section fully overlaps the other a projection 25, on the lower section, strikes the other arm of said latch and forcing it outward releases the catch from the stop 24, thus leaving the upper section of the door free to rise.

The other latch 20 has on one arm a catch 26 that when the two sections fully overlap engages with the stop 25 and locks the two sections together so that the lower section may not move away from the other. When, however, the upper section has reached its lowermost normal position the other arm of latch 20 strikes the stop 24, and this causes it to unhook from and release the lower section which is therefore free to descend while the upper section remains stationary. Any other means of this nature might be used to preserve the two sections under all circumstances in their proper relative positions.

Innumerable doors of this general class have been used or proposed, but my improvement resides in the specific arrange-

ment of chains or their equivalents and the counterweights, whereby no more power is required to raise one section of the door than both sections, whereby one weight only for each side of the door is required and whereby both doors are perfectly counterbalanced in all positions.

The parts not specifically defined in the claims are not essential to the invention and may be greatly varied in construction and in some cases omitted.

What I claim is:

1. In a pier shed door, the combination with two vertically and horizontally movable sections and a shaft by the rotation of which they are raised and moved laterally on the opening of the door, of a sheave fast to said shaft and a sheave loose thereon, a counterweight equal to the weight of both door sections carrying a sheave and a chain or its equivalent connected at one end to the bottom of the lower door section and at its other to the middle of the upper section and running over the said sheaves as herein set forth.

2. In a pier shed door, the combination with the door jamb, upper and lower door sections, and means for guiding the same vertically until they overlap and then laterally until they occupy a horizontal position, of a shaft by the rotation of which said door is opened and closed, a sheave fixed to said shaft and a sheave loose thereon at each side of the door, counterweights equal to the weight of both doors, sheaves carried thereby, and two chains or their equivalents, one end of each connected to the bottom of the lower door section and the other to the middle of the upper section and each running over all of the sheaves at one side of the door, as set forth.

3. In a pier shed door composed of vertically and laterally movable sections and means for opening and closing the door, of latches secured to the top of the upper section, a fixed stop near the normal level of the top of the upper section and a stop at the upper edge of the lower section for engaging with the latches, whereby the two sections will always be preserved in their proper and normal relative positions.

In testimony whereof I hereto affix my signature.

LESLIE McHARG.
